DESIGN FOR A SHOE

Harry Le Roy Sutcliffe, New York, N. Y.

Application July 10, 1942, Serial No. 107,476

Term of patent 3½ years

To all whom it may concern:

Be it known that I, Harry Le Roy Sutcliffe, a citizen of the United States of America, residing in New York city, county of New York and State of New York, have invented a new, original, and ornamental Design for a Shoe, of which the following is a specification, reference being had to the accompanying drawing, forming part thereof.

The figure on the drawing is a front perspec-

tive view of a shoe showing my new design. The opposite side presents substantially the same appearance as the side shown. The dominant feature of my design resides in the portions shown in solid lines.

I claim:

The ornamental design for a shoe, substantially as shown and described,

HARRY LE ROY SUTCLIFFE.
